(57) **CLAIM**

The ornamental design for a bullet bolt with cup washer, as
shown and described.

DESCRIPTION

FIG. 1 is a front view of the bullet bolt with cup washer
showing our new design, with the cup washer affixed to the
bullet bolt. The rear, left and right side elevation views are
mirror images of;

FIG. 2 is an exploded front plan view of the bullet bolt with
cup washer, showing the cup washer in an alternate position;

FIG. 3 is a top, side perspective view of FIG. 1;

FIG. 4 is a second top, side perspective view of FIG. 1,
showing the opposite side of FIG. 3;

FIG. 5 is a bottom, side perspective view of FIG. 1;

FIG. 6 is a second bottom, side perspective view of FIG. 1,
showing the opposite side of FIG. 5;

FIG. 7 is an exploded top, side perspective view of FIG. 2;

FIG. 8 is an exploded bottom, side perspective view of FIG.

2;

FIG. 9 is a second exploded top, side perspective view of
FIG. 2, showing the opposite side of FIG. 7; and,

FIG. 10 is a second exploded bottom, side perspective view
of FIG. 2, showing the opposite side of FIG. 8.
